UNITED STATES PATENT OFFICE

168,689

DESIGN FOR AN AIR CONDITIONER

Axel F. L. Anderson, Detroit, Mich., assignor to
American Blower Corporation, Detroit, Mich., a
corporation of Delaware

Application January 3, 1938, Serial No. 74,056

Term of patent 7 years

To all whom it may concern:

Be it known that I, Axel F. L. Anderson, a citizen of the United States, residing at Detroit, in the county of Wayne and State of Michigan, have invented a new, original, and ornamental Design for an Air Conditioner, of which the following is a specification, reference being had to the accompanying drawing forming a part thereof.

In the drawing:

Figure 1 is a perspective view from the front left-hand corner of an air conditioner showing my new design;

Figure 2 is a detailed view of the wire screen and a portion of the casing shown in Figure 1;

Figure 3 is a rear elevation of the air conditioner; and

Figure 4 is a side elevation thereof.

I claim:

The ornamental design for an air conditioner substantially as shown and described.

AXEL F. L. ANDERSON.
